MANIFOLD FORM REGISTERING DEVICE FOR BILLING MACHINES

Filed August 1, 1922 3 Sheets-Sheet 3

UNITED STATES PATENT OFFICE.

WILLIAM J. WISWALL, OF OAKLAND, CALIFORNIA, ASSIGNOR TO AMERICAN SALES BOOK COMPANY, LIMITED, OF TORONTO, ONTARIO, CANADA, A CORPORATION OF ONTARIO, CANADA.

MANIFOLD FORM-REGISTERING DEVICE FOR BILLING MACHINES.

Application filed August 1, 1922. Serial No. 579,085.

To all whom it may concern:

Be it known that I, WILLIAM J. WISWALL, a citizen of the United States, residing at Oakland, county of Alameda and State of California, have invented new and useful Improvements in Manifold Form-Registering Devices for Billing Machines, of which the following is a specification.

This invention relates to manifolding form registering devices and more particularly to such devices for use with billing machines.

An object of this invention is to improve the form-retaining and registering mechanism both structurally and functionally so as to facilitate the manipulation, and insure greater accuracy in the registry of the forms and greater convenience in handling the records.

Other objects of the invention will in part be obvious and will in part appear hereinafter.

The invention accordingly comprises the features of construction, combinations of elements, and arrangement of parts, which will be exemplified in the constructions hereinafter set forth and the scope of the application of which will be indicated in the claims.

For a fuller understanding of the nature and objects of the invention reference should be had to the following detailed description taken in connection with the accompanying drawing, in which:

Fig. 1 is a side elevation of a billing machine partly broken away showing the application of the invention;

Fig. 2 is a detail plan view of the carbon holder carriage showing the registering mechanism attached thereto;

Fig. 3 is a central, vertical, longitudinal section on line 3—3, Fig. 2;

Fig. 4 is a cross section on line 4—4, Fig. 2;

Fig. 5 is a detail perspective view of the spring latch employed in conjunction with the locking bar of the registering mechanism;

Fig. 6 is a detail view of the pin retracting pawl of the registering mechanism;

Fig. 7 is a cross section on line 7—7, Fig. 2, showing the registering mechanism and

the locking bar employed in conjunction therewith;

Fig. 8 is an enlarged detail sectional view 55 of the typewriter cylinder and the gauge plate carried thereby;

Fig. 9 is a front view of the gauge plate; and

Fig. 10 is a plan view showing a portion 60 of one of the form strips.

The character A designates in general the frame of a billing machine or the like and the character B the auxiliary frame adapted for support of the forms.

This billing machine, has, as illustrated, a platen 2 mounted upon a carriage 3. This platen is rotatable about a shaft 2^a, eccentric to it, from the position shown in solid lines in Fig. 8 to the position shown in dotted 70 lines and is restrained from rotation by a lever 4 operating a catch 5 adapted to engage a screw 5^a on the carriage support.

Extending rearwardly from the carriage are supporting rods 6 which are connected 75 together by cross rods 6^a and 6^b to form an auxiliary carriage in turn supported by anti-friction rollers 7^a running upon transverse track bars 7, whereby the auxiliary carriage may move transversely to the frame with the carriage 3. Supported upon the auxiliary carriage is a carriage 8 upon which the carbon blades are supported for movement toward the platen as the forms are filled in, and back again as a new set of forms is prepared, as will be later described. For the purpose of effecting this movement of the carbon blade carriage, there is provided a handle 9 attached to the carriage 8 as at 10.

Means are provided for feeding a plurality of printed forms through the device and maintaining the correct registry of the superposed forms while passing through the machine. To this end there is preferably provided means adapted automatically to align the forms on the completion of the operation on each form, and the feeding mechanism and web supply are so designed and correlated that this registry is maintained during the filling-in operation.

This mechanism comprises a manually operated registering device, generally indicated at 11, and an automatically actuated registering device, generally indicated at 12, and

100

these devices are preferably so interrelated that one may maintain the alignment while the other is being adjusted relative to the sheets.

- 5 The sheets adapted to be used with this book may be provided in continuous webs having the forms printed thereon in succession as shown at 14, 15, 16, and there may be provided, a weakened portion 18 between the 10 forms to facilitate the separation of the forms and means associated with each form as for example, control apertures 17, in definite relation to each printed form, so that exact registry of the forms may be secured 15 by cooperation of the machine with said apertures.
- Within certain aspects of this invention any suitable source of web supply may be used but particular advantages are obtained 20 when a sufficient number of webs to form the desired number of records are superposed with the sheets folded back and forth upon each other in a zigzag fashion to form superposed sets of superposed record sheets. This 25 folding is preferably done at the weakened portion separating the sheets. In this manner each sheet tends normally to lie in flat condition while in use while the interengagement of sheets in the pad causes them to 30 tend to be fed together and in registry. As illustrated such a pad is provided at 19 and the various superposed webs thereof are fed to the machine together as will be herein-after described.
- 35 The manual registering mechanism comprises a plate 20 extending, when in operative position, generally upward and to the rear from the upper side of the platen, and a head member comprising a cross plate 21 40 clamped to the underside of the plate 20 by a bar 24, held in place by clamping screws 23. This cross plate 21 carries pins 25 in position to correspond with the control apertures 17 in the web and the plate 20 has 45 slots 22 through which the pins 25 and the screws 23 may project to permit the adjustment of the registering member 11 upon the plate 20 in accordance with the length of the form upon the web.
- 50 For the purpose of retaining the sheets upon the pins 25 a clamp 26 is spring-hinged as shown at 28, and extends over and presses upon the sheets; it is provided with a handle 27, to assist in its manipulation.
- 55 A handle 29 is provided upon the bar 24 to facilitate adjustment of the head.

The automatic registering mechanism is arranged to move with the sheets during the filling in operation and to be moved relative to the sheets in preparing for the filling in of another form and to this end it is conveniently attached to the carbon blade carriage 8. As illustrated it comprises a plate 31 extending rearwardly from the carbon blade carriage 8 and attached thereto by

clamping screws 30. Beneath the plate 31 is a cross bar 32 carrying aligning pins 34 in position to cooperate with the control apertures 17 of the web. This bar 32 is mounted on guides 33 for movement to and from the plate 31 to cause the pins to be retracted and project through orifices 34^a in the plate 31 and springs 33^a surrounding guides 33 cause the pins to be projected upwardly through the orifices 34^a unless otherwise restrained.

For the purpose of retracting the pins a lever C is pivoted at 36 to the plate 31 in position to bear downwardly upon the bar 32 and has an operating arm 37 extending downwardly and to the rear in position to engage a trip rod D upon the auxiliary carriage as the carbon blade carriage travels toward the billing machine during the filling in of a form.

With this construction it will be clear that once the pins have entered the apertures in a sheet, they, together with the carbon blade carriage, will travel with the webs until the arm 37, engages the trip rod D, whereupon the pins will be withdrawn to permit the movement of the webs independent of the pins 34.

In order to permit the adjustment of the trip rod D to the length of the particular form to be filled in it is arranged to be movably attached to the rods 6. As illustrated it comprises a cross rod extending between the two rods 6, with its ends bearing upon them respectively as at 38 and 39 and so that it may be clamped between them. As arranged, a stud is attached to a contact member 38 on which the sleeve D may rotate and a corresponding stud is attached to the member 39 which is screw-threaded into the end of the sleeve D whereby the rotation of the sleeve D upon the two studs will project the member 39 to clamp between rods 6.

Cooperating with the plate 31 and the pins 34 is a clamping bar 42 hinged at one end as shown at 44 and having a latch 45 at the other end, whereby it may be swung from a position to cooperate with the pins to a position to expose them as shown in Figure 7 and this rod may conveniently be in the form of a tube having openings through its walls as shown at 44^a to receive the ends of the pins 34.

Suitable side guides 43 may be provided upon the plate 31 to maintain the alignment of the webs.

To permit the severance of the sheets after they have been written upon, a severing blade 60 is provided adjacent to the platen and for the purpose of limiting the backward movement of the carbon blade carriage 8 a stop 70 may be mounted upon the rods 6 and to permit adjustment for various forms this stop is made adjustable.

The operation of the device is as follows: To feed the machine the cylinder-releasing lever 4 is first depressed to release the latch 5 and the handle extension 29 is grasped to 5 swing the plate 20 and the platen in a forward direction to assume the dotted line position shown in Fig. 8. This forward movement of the gauge plate elevates the platen releasing its feed and thereby places it in a 10 position to permit the several superposed sheets to be easily entered. The clamping bar 42 of the automatic registering device is next released and completely opened. The carbon blade carriage 8 is moved to the position 15 shown in Fig. 1 by means of the handle 9 and the machine is then ready to receive the printed forms.

The zigzag folded book, indicated at 19, is placed behind the auxiliary frame, as shown 20 in Fig. 1, and the free ends of the continuous zigzag folded sheets are passed through the primary paper guide on the intermediate carriage as indicated at 50. The sheets are next passed over the plate 31, care being 25 taken that the sheets are passed downwardly between the side guides 43. The sheets are then pulled in a forward direction until one or two sets of forms have passed the pins 34, or in other words until the pins 30 34 register with the punched holes 17^a of the second or third set of forms as shown in Fig. 10. The pins 34 are then passed through the punched portions 17^a of the several superposed forms and the clamping bar 35 42 is swung back into position and locked by means of the spring latch 45.

The upper webs are now turned back over the clamping bar in order to permit a carbon blade carrying its carbon sheet to over- 40 lie the lower web. The carbon sheets and webs may then be caused to alternate, the carbon blades being attached to the carbon blade carriage in any convenient manner.

The free or forward ends of the super- 45 posed forms with the carbon sheets interposed between them are now grasped and passed between the cylindrical platen 2 and cutting plate 60. The plate 20 is thereupon returned to its normal position carrying 50 with it the platen 2 to cooperate with the rest of the billing machine feed mechanism. The filling in of the forms may then be done, the webs being fed by the rotation of the platen.

To bring a new set of forms into position 55 upon the completion of the filling in, the webs are carried up over plate 20 until the control apertures 17 in the advance end thereof may be impaled upon the pins 25 to be held in place by the clamp 26.

The adjustment of the head 24 should be such that the lower edge of the first form is now opposite the cutting edge of the cutting bar 60. The adjustment of the trip rod D 65 will be such that with the webs in this posi-

tion the pins 34 will be withdrawn from engagement with the control apertures 17.

The plate 20 may now be swung forward again in the dotted line position releasing the billing machine feed mechanism from engagement with the webs whereupon the carbon blade carriage may be grasped by its handle 9 and moved to the rear withdrawing the carbon sheets from registry with the filled-in form, to the next succeeding form, until the pins 34 engage the control apertures 17 of the next succeeding sheets and the carbon blade carriage engages the stop 70. It is preferable that the control apertures be engaged slightly in advance of the stop 70 in order that the sheets be placed under slight strain to straighten them, and it will be noticed that the sheets are at this time stretched straight between the two aligning mechanisms.

The plate 20 may now be returned to its normal position, the webs disengaged from the pins 25, and the filled-in forms torn off across the cutting blade ready for the filling in of the next form.

By the above construction it will be clear that the several webs are held in alignment during the filling-in operation and caused to advance together with the carbon sheets all as a single sheet and they are held in this clamped position by the pins 34 until the filling-in is completed. They are thereupon again clamped in registering position by the pins 25 and held in registry by these pins until the filling-in of the preceding form is completed.

Furthermore, during the retraction of the carbon blade carriage to the next succeeding set of forms, it will be noted that as soon as the retracting action has commenced, the lever 37 being out of engagement with the trip rod D, the pins 34 are projected into the pathway of the web and bear frictionally against it to bring it under tension, and in co-operation with the side guides 43, straighten out any irregularities or wrinkles that may be in it. When the pins 34 reach and penetrate the control apertures they may engage them at the sides thereof to bring the webs under tension and it is to be noted that at this time that by reason of the position of the platen, the webs are substantially straight between the pins 25 and the pins 34. Thus each web is stretched substantially independently of the others between the control apertures to bring it into exact alignment. Furthermore, the stop 70 is positioned to cooperate to check retraction of the carriage 8 somewhat after the pins 25 are automatically projected to engage the apertures so as to bring the superposed sheets into longitudinal alignment, without however exerting such force as to tear the edges of the control apertures.

It will be evident furthermore that at the

time the pins are bearing upon the webs in the reverse movement to straighten out the forms they are bearing at a point where the webs are not in contact with the carbon sheets. Furthermore, by reason of the fact that a web supply is utilized in which the different printed forms are at all times in register and from which they are fed to the billing machine in register there is no danger of one web creeping so far upon another to bring the control apertures in the one web out of alignment with those of the other.

Since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In a machine of the class described, comprising, in combination, a plurality of strips having successive forms printed thereon and control apertures in definite relation to the forms, a platen, printing mechanism, means for moving said strips relative to said printing mechanism, a guide member over which said strips are fed, pins upon which the apertures in a set of forms may be impaled, said pins, said platen, and said guide member being relatively movable from a position to support said strips between said pins and said guide member, to a position to bring said strips substantially into contact with said platen.

2. In a machine of the class described, comprising, in combination, a plurality of strips having forms printed thereon and control apertures bearing definite relation to said forms, a carbon carriage, pins associated with said carbon carriage, spring-pressed to engage when unrestrained said strips and penetrate said apertures to bring said forms into registry, and automatic means for withdrawing said pins when a predetermined feed has been made.

3. In a machine of the class described, comprising, in combination, a plurality of superposed strips having forms printed thereon and apertures in definite relation to said forms, a pair of elements adapted to enter apertures in different sets of forms, one of said elements being movable away from the other to stretch said strips.

4. In a machine of the class described, the

combination with the carbon carriage and the cylinder carriage of a billing machine, which carriages are adapted to receive and support a series of continuous superposed sheets having successive forms printed thereon and control apertures bearing definite relation to said forms, said carbon carriage being adapted to advance in unison with the form sheets while they are being typed upon, means for manually returning the carbon carriage when a set of forms has been filled in, means on the cylinder carriage for entering and aligning the apertures of the filled in forms and retaining the forms in alignment during the return movement of the carbon carriage, and means carried by the carbon carriage adapted to penetrate the apertures of a succeeding set of forms during return movement of the carbon carriage, and to align the adjacent superposed printed forms.

5. In a machine of the class described, the combination with the carbon carriage and the cylinder carriage of a billing machine, which carriages are adapted to receive and support a series of continuous superposed sheets having successive forms printed thereon and control apertures bearing definite relation to said forms, said carbon carriage being adapted to advance in unison with the form sheets while they are being typed upon, a means for manually returning the carbon carriage when a set of forms has been filled in, means on the cylinder carriage for entering and aligning the apertures of the filled in forms and retaining the forms in alignment during the return movement of the carbon carriage and means carried by the carbon carriage adapted to penetrate the apertures of a succeeding set of forms during return movement of the carbon carriage and to align the adjacent superposed printed forms, said last mentioned means being adapted to exert a longitudinal pull upon the sheets.

6. In a machine of the class described, the combination with the carbon carriage and the cylinder carriage of a billing machine, which carriages are adapted to receive and support a series of continuous superposed sheets having successive forms printed thereon and control apertures bearing definite relation to said forms, said carbon carriage being adapted to advance in unison with the form sheets while they are being typed upon, a means for manually returning the carbon carriage when a set of forms has been filled in, means on the cylinder carriage for entering and aligning the apertures of the filled in forms and retaining the forms in alignment during the return movement of the carbon carriage, means carried by the carbon carriage adapted to penetrate the apertures of a succeeding set of forms during return movement of the carbon carriage and to

5 align the adjacent superposed printed forms, said last mentioned means being adapted to exert a longitudinal pull upon the sheets, and a stop to limit the movement of the carbon carriage to limit said pull.

10 7. In a machine of the class described, in combination, a carbon carriage, paper strips, a platen, aligning pins on the carriage for engaging control apertures in the paper strips to hold them in registry as they are drawn toward the platen, means controlled by the forward movement of the carriage for releasing the pins and means for holding the pins for engaging the apertures to hold the strips during the return movement of the carriage.

15 8. In a machine of the class described, in combination, a carriage having means for supporting and advancing superposed strips provided with control apertures, a second carriage mounted to travel on the first mentioned carriage with the strips, pins on the second mentioned carriage for engaging the control apertures in the strips to hold the strips in alignment, and for constraining the second mentioned carriage to travel with the strips, normally active means to extend the pins, means controlled by the forward movement of the second mentioned carriage for retracting the pins so they are disengaged from the control apertures to permit the return movement of the second mentioned carriage, and other pins supported by the first mentioned carriage for engaging the control apertures to hold the strips during the return movement of the second mentioned carriage.

20 9. In a machine of the class described, comprising, in combination, a support for a plurality of strips having successive forms printed thereon and control apertures in definite relation to the forms, a guide member over which said strips may be passed, means for retaining the ends of said strips including pins adapted to project through the control apertures of the end form, a carriage movable with and contrary to the strips carrying pins adapted to cooperate with the control apertures to retain the strips in alignment, and means for automatically releasing said pins to permit their reverse movement when said strips have moved a predetermined distance.

25 10. In a machine of the class described, in combination, a carriage having means to support and advance paper strips provided with control apertures, a second carriage, normally active pins on the second carriage for engaging the control apertures and means controlled by forward movement of the carriage with the strips to release the pins.

30 11. In a machine of the class described, in combination, a carriage having means to support and advance paper strips provided

35 with control apertures, a second carriage, normally active pins on the second carriage for engaging the control apertures, means controlled by forward movement of the carriage with the strips to release the pins, and a removable guard for the free ends of the pins to facilitate threading of the strips.

40 12. In a machine of the class described, in combination, a frame, a carriage having means to support and advance superposed strips of paper having control apertures, a second carriage mounted to travel with the strips, pins on the second carriage for engaging the control apertures, normally active means to extend the pins above the carriage and a trip adjustable relative to the frame for retracting the pins.

45 13. The combination with the carbon blade carriage and the cylinder carriage on a billing machine which carriages are adapted to receive and support a series of continuous superposed sheets having successively arranged forms printed thereon and control apertures in definite relation to said forms, means for automatically advancing the carbon blade carriage in unison with the form sheets while they are being typed upon, means for manually returning the carbon blade carriage, a form registering device supported by the carbon blade carriage, and means for automatically releasing said form registering device when the forms being filled in or typed upon are completed, said means also adapted to automatically re-engage the form sheet and laterally and longitudinally align the same during return movement of the carbon blade carriage.

50 14. The combination with the carbon blade carriage of a billing machine, of a plate supported thereby, a pair of pins projecting through the plate, a clamping bar extending across the plate and cooperating with the pins, and means for automatically projecting and retracting the pins with relation to the plate during forward and return movement of the carbon blade carriage.

55 15. The combination with the carbon blade carriage of a billing machine, of a plate supported thereby, a pair of pins projecting through the plate, a clamping bar extending across the plate and cooperating with the pins, means for automatically projecting and retracting the pins with relation to the plate during forward and return movement of the carbon blade carriage, and adjustable means for regulating the period of depression and projection of said pins.

60 16. The combination with the carbon blade holder of a billing machine, and the carriage upon which the holder is longitudinally movable, of a form registering device supported by the holder, and means for rendering said form registering device inoperative when the holder substantially

- reaches the limit of its forward movement, said means also automatically rendering the registering device operative during return movement of the holder.
- 5 17. In a billing machine of the character described a carbon blade holder, a carriage upon which said holder is longitudinally movable, a plate supported by the holder, a pair of form aligning pins on said plate, a 10 trip lever on the plate adapted to depress the pins with relation to the plate, and a trip bar on the carriage engageable with the trip lever to automatically depress and project the pins.
- 15 18. In a billing machine of the character described a carbon blade holder, a carriage upon which said holder is longitudinally movable, a plate supported by the holder, a pair of form aligning pins on said plate, a 20 trip lever on the plate adapted to depress the pins with relation to the plate, a trip bar on the carriage engageable with the trip lever to automatically depress and project the pins, and a clamping bar pivotally attached to the plate straddling and cooperating with the pins.
19. In a machine of the class described, comprising, in combination a support for a plurality of superposed strips having forms 30 thereon and control apertures bearing definite relation to said forms, a carbon carriage movable with and independent of said strips for carrying carbon sheets, pins associated with said carbon carriage adapted to engage said control apertures to retain said strips in alignment during motion with said carriage and means for automatically withdrawing said pins on the completion of the filling in of said forms.
- 40 20. In a machine of the class described, comprising, in combination, a platen, a support for a plurality of superposed strips having control apertures therein, said platen being movable into and out of engagement with said strips, a carbon carriage movable with and independent of said strips for carrying carbon sheets, means associated with said carbon carriage adapted to engage said control apertures to retain 45 said strips in alignment during motion with said carriage and adapted yieldingly to engage said strips during motion of said carriage contrary to said strip for smoothing said strips.
- 50 21. In a machine in the class described in combination, a plurality of strips having forms printed thereon and control apertures in definite relation to said forms, means for feeding said strips, a carriage movable with 60 and contrary to said strips, having pins thereon, means for projecting said pins through said control apertures and for withdrawing them, means for operating said last mentioned means upon completion 65 of predetermined feeding movement to withdraw said pins, means for restraining said strips with the forms in registry during return movement of the carriage when at a point where said pins will not automatically re-engage the same control openings.
- 70 22. In a machine of the character described, in combination, a carbon carriage, a printing mechanism, a plurality of strips having forms printed thereon and control apertures in definite relation to the forms, a carbon carriage movable with and contrary to the strips, and carrying spring pressed pins adapted to penetrate said apertures, mechanism operative to depress said pins, a trip to operate said mechanism to depress said pins when a predetermined point in the feed has been reached, a gauge and clamp having pins so positioned relative to said trip that when the perforations of one set of forms are placed upon said pins the sheet will be held in registry in position such that on return movement of the carriage the spring pressed pins will not re-enter the same perforations when said pin-operating mechanism is disengaged by said trip.
- 75 23. In a machine of the character described, in combination, means for simultaneously feeding superposed sheets each having similar forms positioned therealong and having a series of control apertures therein bearing definite relation to said forms, a movable carriage for supporting said superposed sheets and advancing with said sheets during feeding movement thereof, and a pin on said carriage and engaging in said apertures to maintain the sheets in longitudinal alignment during feeding thereof.
- 80 24. In a machine of the character described, in combination, means for simultaneously feeding superposed sheets each having similar forms positioned therealong and having a series of control apertures therein bearing definite relation to said forms, a movable carriage for supporting said superposed sheets and advancing with said sheets during feeding movement thereof, a pin on said carriage and engaging in said apertures to maintain the sheets in longitudinal alignment during feeding thereof, means to positively hold the forwardly fed parts of said sheets, said carriage being returnable to initial position after a forward feeding movement thereof, and said pin being engageable in said apertures to effect longitudinal alignment of said forms on the superposed sheets when the carriage is returned to initial position and while said forwardly fed parts are held by said holding means.
- 85 25. In a machine of the character described, in combination, means for simultaneously feeding superposed sheets each having similar forms positioned therealong,

a movable carriage for supporting said superposed sheets and advancing with said sheets during feeding thereof, means to positively hold the forwardly fed parts of said sheets, and means on said carriage to effect longitudinal alignment of said sheets when the forwardly fed parts thereof are held by said holding means.

26. In a machine of the character described, in combination, means for simultaneously feeding superposed sheets each having similar forms positioned therealong, members for simultaneously positively engaging said sheets at longitudinally spaced parts thereof to effect longitudinal alignment of the forms on the superposed sheets, and a movable supporting member for sup-

porting one of said sheet engaging members normally out of alignment with the other sheet engaging member but being movable to bring the stretch of sheets between said sheet engaging members into a substantially straight line.

27. In a machine of the character described, in combination, means for simultaneously feeding superposed sheets each having similar forms positioned therealong, a movable carriage for supporting said superposed sheets and advancing with said sheet during feeding thereof, and means for positively attaching said sheets to said carriage during feeding of the sheets.

WILLIAM J. WISWALL.
